UNITED STATES PATENT OFFICE.

FAY TURPIN, OF CHICAGO, ILLINOIS, ASSIGNOR TO RESEARCH CLUB, INC., OF CHICAGO, ILLINOIS, A CORPORATION OF ILLINOIS.

DESIGN FOR A SIGN OR SIMILAR ARTICLE.

Application filed March 20, 1922. Serial No. 1,261. Term of patent 14 years.

To all whom it may concern:

Be it known that I, FAY TURPIN, a citizen of the United States, residing at Chicago, county of Cook, State of Illinois, have invented a new, original, and ornamental Design for a Sign or Similar Article, of which the following is a specification, reference
being had to the accompanying drawing,
forming a part thereof.

Fig. 1 is a front view, and

Fig. 2 an edge view showing my new design.

I claim:

The ornamental design for a sign or similar article, substantially as shown.
